UNITED STATES PATENT OFFICE

97,413

DESIGN FOR A CARRIAGE ROBE

Saul O. Reyman, Milwaukee, Wis.

Application March 23, 1935, Serial No. 56,007

Term of patent 7 years

To all whom it may concern:

Be it known that I, Saul O. Reyman, a citizen of the United States, residing at Milwaukee, in the county of Milwaukee, and State of Wisconsin, have invented a new, original, and ornamental Design for a Carriage Robe, of which the following is a specification, reference being had to the accompanying drawing, forming part thereof.

The figure in the drawing is a plan view of the robe. The back of the robe is substantially

straight on the sides and bottom, and has the curved ornamental collar at the top thereof, compared with the front or plan view as shown in the drawing, it is relatively plain.

I claim:

The ornamental design for a carriage robe as shown and described.

In testimony whereof, I affix my signature at Milwaukee, Wisconsin.

SAUL O. REYMAN.
